UNITED STATES PATENT OFFICE.

PATRICK McFADDEN, OF PHILADELPHIA, PENNSYLVANIA.

HARNESS-TERRET.

SPECIFICATION forming part of Letters Patent No. 282,743, dated August 7, 1883.

Application filed June 7, 1883. (No model.)

To all whom it may concern:

Be it known that I, PATRICK McFADDEN, a citizen of the United States, residing at Philadelphia, in the county of Philadelphia and State of Pennsylvania, have invented certain new and useful Improvements in Harness-Terrets; and I do hereby declare the following to be a full, clear, and exact description of the invention, reference being had to the accompanying drawings, which form part of this specification, in which—

Figure 1 is a vertical section, and Fig. 2 a side elevation, of my improvement.

My invention has for its object to provide a terret provided with a base loop or band for the passage of a sliding back-band, said base having means for readily attaching it to and permitting its detachment from the saddle-plate.

20 A further object of my invention is to provide a terret-base of simple construction, which may be screwed into the saddle-plate and into which the terret-ring may be screwed, as hereinafter fully described.

25 Referring to the accompanying drawings, A indicates a terret, comprising a base, B, and ring C. The base B is in the form of a loop or oblong ring, having top and bottom bars, b', and sides b² b². Projecting from the bottom bar, b', is a threaded stud or male screw, b³, and projecting from the upper bar, b, is a boss, b⁴, having a threaded socket or female screw, b⁵. The ring C has a male screw, c, which engages with the female b⁵; or, if desired, the ring C and base B may be integral and inseparable.

30 The screw b³ is intended to enter a metallic plate with threaded opening in the harness-saddle, or into a nut or burr secured in said saddle.

35 The base B, being open, affords a passage-

way for a sliding back-band. To avoid cutting said band on the edges of the bar b', the latter may be made convex on its upper side, and to reduce friction a roller having bearings 45 for its journals in the sides b² b² may be provided.

It will be noted that the ring C stands transverse of the opening in the base, inasmuch as the reins, which pass through the terret-rings, 50 cross the saddle, while the back-band rests lengthwise of the latter.

A terret of this construction affords a passage-way and guide for a sliding back-band. It can readily be attached to and detached from 55 as well as adjusted in position on a harness-saddle. When the ring is made separate from the base, it can be readily taken off for cleaning, replating, or gilding, or to permit the substitution of a different pattern of ring when- 60 ever desired.

What I claim as my invention is—

1. A terret having an open base for the passage of a sliding back-band, a rein-opening transverse of and above said open base, and a 65 central projecting threaded boss or screw for insertion in a saddle plate or burr, substantially as shown and described.

2. A terret comprising a base, B, with central projecting screw on its under side, a few 70 male-threaded boss on its upper side, and a ring, C, with screw c, fitting the female screw in the base, substantially as shown and described.

In testimony that I claim the foregoing I have 75 hereunto set my hand this 5th day of June, 1883.

PATRICK McFADDEN.
